PHILANDER H. BETTS, OF BELMAR, NEW JERSEY, ASSIGNOR TO WESTERN ELECTRIC COMPANY, INCORPORATED, OF NEW YORK, N. Y., A CORPORATION OF NEW YORK

ELECTRIC WAVE TRANSMISSION SYSTEM

Application filed December 13, 1924. Serial No. 755,612.

This invention relates to electric wave transmission systems and more particularly to means having improved transmission characteristics for coupling space discharge tubes.

The design of space discharge amplifier systems for high frequency waves involves, among others, the problem of making the system sufficiently selective and stable without decrease in efficiency. An important element of an amplifier system is the coupling circuit between successive tubes. The coupling circuit very frequently includes tuned circuits, and coupling circuits of this kind may introduce undesired effects into the system which are difficult to eliminate. One such effect is distortion caused by the resonant characteristics of inductances such as transformer windings. The characteristic referred to results from the fact that the inductance coils are not aperiodic at high frequencies but on the contrary are resonant at some frequency determined by their inductance and distributed capacity.

Another problem encountered in space discharge tube systems for transmitting high frequency waves is that of preventing parasitic oscillations or singing. One method of preventing such oscillations is that of neutralizing the inherent capacity of the discharge tubes by means of balancing condensers. The application of this method, in certain instances, however, may cause a reduction in the efficiency of wave transmission. This will be especially true when the impedances of circuits connected to the space discharge tubes have not been properly proportioned with respect to the impedance of the tubes themselves.

An object of the invention is to efficiently transfer waves between successive stages of a multi-stage space discharge tube system.

Another object is to prevent the production of parasitic oscillations in amplifier systems.

A further object is to couple successive tubes of a space discharge tube system in such manner as to match the impedance of the tubes by their connected circuits whereby waves may be efficiently transmitted.

A still further object is to negative the effect of the resonance property of inductances included in a coupling circuit.

An additional object is to cause regeneration in a space discharge tube system without the production of parasitic oscillations.

A feature of the invention relates to a coupling means for space discharge tubes which is specially adapted to neutralization of the tube capacity and which has impedance elements designed to match the tube impedances.

Another feature of the invention concerns a tuned coupling element for space discharge tubes which has its inductance elements so arranged that no undesired effects are produced by virtue of their individual resonance properties.

A still further feature is represented by a coupling means adapted to permit neutralization of the capacity of a space discharge tube independent of balance in the input circuit of the tube.

An additional feature relates to a feedback coupling for a space discharge tube for causing regeneration without the production of oscillations.

In this invention, a space discharge system comprising a plurality of space discharge tubes may have its tubes coupled in tandem by means of a resonant circuit including inductance and capacity elements. In addition, means is provided for balancing the capacity between electrodes of certain tubes to prevent the production of parasitic oscillations. In order to prevent undesired effects caused by the resonance properties of inductance elements forming a part of the coupling circuit, all of these elements are arranged so that their individual properties are merged into that of a single resonant circuit. Portions of these inductance elements are also included in circuits connected to the space discharge tubes of the system in such manner as to match the impedance between the electrodes of the tubes to which they are connected.

Moreover, the coupling circuit is arranged to provide paths of balanced impedance between the cathode and control electrode and cathode and anode respectively of certain tubes.

The path between the cathode and anode may include a capacity for neutralizing the capacity of the tube. By virtue of this arrangement, the tube capacity will be balanced at all frequencies, as would not be the case if these impedances were not balanced, because the coupling between these impedances is a function of frequency and inequality in the impedances would thus cause unbalance at certain frequencies. In addition the phase relations of currents in the balanced paths of the arrangement of the invention will remain constant with frequency.

The invention will be more readily understood and the additional features and objects thereof will be more apparent from the following detailed description considered in connection with the drawings wherein:

Fig. 1 represents a radio receiving system, including a radio frequency amplifier and the tuned coupling arrangement of this invention;

Fig. 2 represents a radio receiving system having a modified form of the coupling circuit illustrated in Fig. 1;

Fig. 3 represents another form of radio receiving system having a tuned coupling circuit with means for causing regeneration to take place in one tube of the system.

Like reference characters have been used in the several figures of the drawings to indicate like parts.

In Fig. 1, the radio receiving system includes a loop antenna 10, a high frequency amplifier 15, a detector 20, and a signal receiver 25. The high frequency amplifier 15 includes the space discharge tubes 16 and 17 arranged in tandem by means of a coupling circuit 18. The space discharge tube 16 has an input circuit connected to its control electrode and cathode which includes one-half of the winding of loop antenna 10 in series with polarizing battery 9. The midpoint of the loop is connected to the cathode of tube 16 and one outer terminal is connected to the control electrode. The opposite terminal of the loop is connected to the anode of tube 16 by a path including the balancing condenser 11. The loop antenna 10 is arranged to be tuned by an adjustable condenser 12, which is connected between its outer terminals.

The coupling circuit 18 comprises a closed tuned loop including in series, adjustable condenser 19, inductance 13, fixed condenser 14 and inductance 21. Inductances 13 and 21 may, if desired, be inductively coupled but this is entirely optional. The output circuit of tube 16, which is connected to its cathode and anode, includes a portion of the inductance 13 in series with space current battery 22. The impedance of inductance 13 included in the output circuit of tube 16 is preferably of such value as to match the impedance of the tube. A portion of the inductance 21 having an impedance arranged to match the

input impedance of tube 17 is connected to the control electrode and cathode of the tube in series with a polarizing battery 24. A portion of inductance 13 equal to that portion of inductance 21 included in the control electrode circuit of tube 17 is connected to the anode of tube 17 by a path including a second condenser 23, arranged to balance the capacity between control electrode and anode of tube 17. The condenser 14 included in the coupling circuit 18 serves to block current from batteries 22 and 24. Condenser 14 is of such capacity as to have a negligible effect upon the frequency of resonance of circuit 18.

The portion of inductance 13 included in the output circuit of tube 16 will, in general, have an impedance less than the inductance of 21 included in the input circuit of tube 17, hence there is produced a step-up of voltage from the output circuit to the input circuit.

The output circuit of tube 17 is coupled to the input circuit of detector tube 26 by a second tuned coupling circuit 27 comprising adjustable condenser 19' arranged in series with inductance 13', condenser 14' and inductance 21' in a closed loop. Inductances 13' and 21' are preferably free of any inductive coupling with inductances 13 and 21. A suitable average potential is maintained upon the control electrode of tube 26 by a blocking condenser 27, shunted by a leak resistance 28. A receiving device 25 in series with a source of space current 29, represented as a battery, is connected between the cathode and anode of tube 26.

No balancing condenser is provided for tube 26, since no danger of oscillations being produced is present, because of the low impedance of the tube output circuit to high frequency waves.

When a carrier wave modulated in accordance with signals is impressed upon the loop antenna 10, corresponding waves are produced in the input circuit of tube 16, amplified by tube 16 and supplied from the output circuit of tube 16 to tube 17 by means of a coupling circuit 18.

It is to be particularly noted that the inductances 13 and 21 are both wholly included in the coupling circuit 18, which is preferably tuned to the mean of the band of frequencies that it is desired to receive. By including the inductances 13 and 21 in the single resonant circuit 18, their individual resonance properties are merged into the single resonant characteristic of the tuned coupling circuit 18, hence undesired effects from the resonant characteristics of these inductances are prevented. By including in the input and output circuit respectively, of tubes 16 and 17 only such portions of the inductances 13 and 21 as will match the impedance of the tubes, the voltage produced upon the tubes by waves in these circuits will be increased

and the efficiency of transfer of the waves from tube to tube will be correspondingly improved.

5 The signal modulated waves supplied to tube 26 are detected and resulting waves of signal frequency are supplied to the receiving device 25.

10 The system represented in Fig. 2 includes an open antenna 10 coupled to the input circuit of a high frequency amplifier 15, which is arranged to supply waves to the input circuit of a detector 20, having a receiving device 25 included in its output circuit. The antenna 10 is connected to ground in series 15 with a loading inductance 30, adjustable condenser 31, and primary winding of a variable transformer 32. The secondary winding of transformer 32 is shunted by an adjustable condenser 33 and so forms a resonant circuit, 20 which is connected to the control electrode and cathode of tube 16', in series with polarizing battery 34. The output circuit of tube 16' is coupled to the input circuit of tube 26' by a tuned coupling circuit 35, which 25 is similar to the corresponding circuit 18 of Fig. 1.

30 The receiving circuit shown in Fig. 2 includes a condenser 36 arranged to balance the inherent capacity of tube 16', independent of balance of the input circuit of the tube. This arrangement has an added advantage in that the entire voltage across the secondary winding of transformer 32 is applied to the control electrode of tube 16', whereas if 35 the capacity of tube 16' were neutralized by a connection from the anode to its control electrode through the inductance of this winding, only one-half of the voltage across the winding would be applied to the control electrode. The circuit shown in this figure 40 functions in a manner substantially the same as that described in connection with Fig. 1 and hence will be understood without further explanation.

45 The circuit diagram of Fig. 3 represents the present invention as applied to a somewhat more practical form of radio receiving system. The antenna 10 in this instance is coupled to the input circuit of a high frequency amplifier 15, comprising the tube 16. A detector tube 37 has its input circuit connected to the output circuit of tube 16 by a resonant coupling circuit 18. The output circuit of tube 37 is transformer coupled to the input circuit of a low frequency amplifier 38, arranged to supply waves to a signal receiver 25.

50 The circuit here shown embodies features included in the circuits of both Figs. 1 and 2. For example, the balancing condenser 36 is arranged to neutralize the capacity of tube 16, independently of balance of the input circuit of the tube as in Fig. 2 and a portion 55 of the inductance 13 such as to match the

output impedance of tube 16 is included in its output circuit as in Fig. 1.

A blocking condenser 39 in the input circuit of tube 37, in cooperation with a leak resistance 40, is provided in order to maintain a suitable average potential upon the control electrode of the tube. The output circuit of tube 37 includes the primary winding of a low frequency transformer 41 which is shunted by a path including a by-pass condenser 43 connected by means of a switch 42. The condenser 43 supplies a low impedance path for high frequency waves around the winding of transformer 41. The transformer 45 preferably offers a high impedance to high frequency waves. A common battery 44 supplies space current to tubes 16, 37 and 38 in parallel. This battery is shunted by a condenser 45 which provides a low impedance path for high frequency waves. The cathodes of tubes 16, 37 and 38 are heated in series by a common battery 46 arranged in series with the adjustable resistance 47. The output circuit of tube 37 is coupled to the input circuit of tube 38 by means of transformer 41.

An adjustable condenser 48 is arranged to be connected between the anodes of tubes 16 and 37 by the operation of switch 42 which at the same time disconnects condenser 43 from transformer 41. The condenser 48 thus supplements the capacity of tube 37 in providing a feed back path between its output and input circuits to allow increased regenerative action. By adjusting condenser 48 the proper amount of regeneration necessary to secure the maximum amplification without the production of parasitic oscillations may be obtained. The primary winding of transformer 41 is designed to have high impedance for high frequency waves in order that these waves may be caused to traverse the condenser 48 in preference to the winding of the transformer which is connected in parallel with the condenser between the anode and cathode of tube 37.

The invention, which has here been described in connection with certain specific embodiments, is not to be limited to the specific arrangements disclosed but only as indicated by the scope of the appended claims.

What is claimed is:

1. In a radio receiving system, a plurality of space discharge tubes, means for supplying high frequency waves to one tube and means for coupling said tube to another tube comprising inductance and capacity elements in a closed loop, said inductance elements being arranged to match the impedances of said tubes to the impedances presented to said tubes by said loop at resonance.

2. In a high frequency transmission system, a plurality of space discharge tubes, means for coupling said tubes comprising capacity elements and inductance elements

- forming a single resonant circuit therewith and arranged to match the tube impedances to the impedances presented to said tubes by said resonant circuit.
3. In a space discharge tube system, a plurality of space discharge tubes having input and output circuits, means for coupling an output circuit to an input circuit comprising a single resonant loop, inductance elements in said loop having portions only included in said coupled circuits, said portions respectively having points at the same alternating current potential and also respectively having points at alternating current potentials opposite to each other.
4. In a space discharge tube system, a plurality of space discharge tubes, input and output circuits for said tubes, means for coupling an output circuit of one tube to an input circuit of another tube and maintaining the alternating current voltage from the cathode to the anode in said output circuit opposite in sign to the alternating current voltage from the cathode to another point on said input circuit, said means comprising a single resonant circuit, an impedance element included wholly in said resonant circuit and only partially in one of said first mentioned circuits.
5. In a high frequency transmission system, a plurality of space discharge tubes, input and output circuits for said tubes, an impedance included partly in said output circuit, a second impedance included partly in said input circuit, and a resonant circuit including both said impedances, the portions of said impedances included in said circuits being such as to match the impedances of the respective tubes to the impedances presented to said tubes by said resonant circuit.
6. In an electric wave transmission system, a plurality of space discharge tubes each having an input and an output circuit, a highly selective resonant coupling circuit including a plurality of inductances and a variable tuning condenser, one of said inductances being connected in an input circuit and another being included in an output circuit, and a source of unidirectional plate voltage connected between said inductances, said inductances included in said circuits having mutual induction therebetween.
7. In a radio receiving system, an antenna, a space discharge tube amplifier having an input circuit coupled to said antenna, means for balancing the capacity of said tube independent of balance of said input circuit, a second space discharge tube and a resonant coupling circuit for said tubes including impedances arranged to produce a step-up of voltage in said system and to match the tube impedances to the impedances presented to said tubes by said resonant coupling circuit.
8. A high frequency amplifier including 65 a plurality of thermionic valves in cascade

arrangement, each valve having a grid electrode and an anode, a grid circuit and an anode circuit, inductance means connected in one anode circuit, said inductance means having two terminals at opposite sides of a point thereon, one of said terminals being connected to the anode of its respective valve, said point of said inductance means being connected through a high tension battery to the filament circuit, the other of said terminals being connected through a capacity to the grid electrode of the same valve, and through another capacity to the grid circuit of the next succeeding valve.

9. A system comprising an electric discharge device having an anode and a cathode, an electric discharge device having a discharge control element, a resonant circuit intercoupling said devices, means connecting said anode and said control element to points on said circuit at alternating potentials always opposite to each other with respect to the potential of said cathode, and means for causing a potential on said circuit to control voltage regeneration in said system.

10. A system comprising an electric discharge device having a cathode and an anode, a non-oscillatory electric discharge device having a cathode and a discharge control element, a highly selective tuned loop circuit intercoupling said devices, said circuit including two inductance elements, independent direct current paths respectively including said inductance elements and respectively connecting a pair of points at the direct current potentials of said cathode and said anode of said first device and a pair of points at the direct current potentials of said cathode and said control element of said second device, a source of space current for said first device included in one of said paths, a circuit comprising means for energizing said cathode of said first device, means for maintaining a point on said space current source at the same alternating current potential as a point on said cathode energizing circuit, and a condenser connected between a point on said circuit and a point on one of said devices for reducing regenerative action in said system.

11. A system comprising electric discharge devices, a single resonant circuit intercoupling said devices and presenting different impedances to said devices respectively, one of said devices having anode and discharge control elements, and a condenser connecting one of said elements to a point on said circuit at a potential equal in value but opposite in sign to that of said other element.

In witness whereof, I hereunto subscribe my name this 11th day of December, A. D. 1924.

PHILANDER H. BETTS.
